Primary Examiner — Kevin K Rudzinski*Assistant Examiner* — Paul D Bohannon(74) *Attorney, Agent, or Firm* — Fross Zelnick Lehrman & Zissu, P.C.; Charles T. J. Weigell, Esq.**(57) CLAIM**

The ornamental design for a chair (leaf), as shown and described.

DESCRIPTION

FIG. 1 is a front perspective view of a chair showing my new design;

FIG. 2 is a right side view thereof, with the left side view being a mirror image thereof;

FIG. 3 is a front view thereof;

FIG. 4 is a back view thereof;

FIG. 5 is a top view thereof; and,

FIG. 6 is a bottom view thereof.

The broken lines shown in FIGS. 1 and 6 are for the purpose of illustrating environmental subject matter and form no part of the claimed design.
